UNITED STATES PATENT OFFICE.

JOHN P. BROPHY, OF CLEVELAND, OHIO, ASSIGNOR TO THE CLEVELAND MACHINE SCREW COMPANY, OF SAME PLACE.

ATTACHMENT FOR AUTOMATIC LATHES.

SPECIFICATION forming part of Letters Patent No. 681,188, dated August 27, 1901.

Application filed August 2, 1900. Serial No. 25,647. (No model.)

To all whom it may concern:

Be it known that I, JOHN P. BROPHY, a citizen of the United States, and a resident of Cleveland, county of Cuyahoga, and State of Ohio, have invented a new and useful Improvement in Attachments for Automatic Lathes, of which the following is a specification, the principle of the invention being herein explained and the best mode in which I have contemplated applying that principle, so as to distinguish it from other inventions.

My invention relates to attachments for automatic lathes, and particularly to devices for cutting off the work independently of the cross-slide, whereby the use of an extra tool is permitted and a piece finished in one operation of the lathe.

The annexed drawings and the following description set forth in detail certain mechanism embodying the invention, such disclosed means constituting but one of various mechanical forms in which the principle of the invention may be used.

In said annexed drawings, Figure I represents an end elevation of said attachment, showing in addition lathe portions immediately adjacent thereto. Fig. II represents a top plan view of said invention, showing adjacent portion of said lathe; and Fig. III represents a front elevation of same.

Secured to the frame A of the machine by means of suitable screws is a stationary support B, located transversely with respect to the axis of rotation of the lathe's head-stock. In said support is formed a slide-bearing b^1 , in which is located a bar B' , one extremity of which is formed with a wedge b' . The opposite end of said bar is formed with a contact-bearing b^2 , upon which bears a roller c , mounted upon a rocker-arm C, pivoted upon the support B, as shown in Fig. I. Contact between said roller and the bar is maintained through the agency of a helical spring b^3 , whose extremities are suitably secured to the support and bar, respectively. The free extremity of the rocker-arm C is provided with a roller c' , which is engaged by a cam D, mounted upon a rotatable shaft D', the rotation of which is effected through the medium of suitable connections with the lathe's driving mechanism. A second slide-bearing b^4 is

formed in the support, in which a cutting-off tool B^2 is located, so as to be reciprocable in a direction transverse with respect to the axis of rotation of the head-stock and with 55 respect to the direction of movement of the bar B' . In the device illustrated the direction of movement of bar B' is horizontal and that of the cutting-off tool vertical. The lower surface of wedge b' engages a roller b^5 , 60 mounted upon said tool, contact between said wedge and roller being maintained through the agency of a helical spring b^6 , the extremities of which are secured to the support and tool, respectively. The shaft upon 65 which the cam D is mounted is connected with driving mechanism (not shown) in a manner such as to effect one revolution thereof in a period of time in which the work or head-stock is given a plurality of revolutions, 70 whereby the cutting-off tool is caused to operate upon the work after the manner usually employed in tools utilized for such purpose. One wall of said slide-bearing b^4 is formed by an adjustable clamp b^7 , whereby tools of different thicknesses may be used. 75

In operation the cam D is rotated, thereby effecting one reciprocating stroke of the bar B' , the wedge upon the extremity of which effects the downward or feeding stroke of the cutting-off tool B^2 . Upon the recession of the cam D the spring b^8 effects the return movement of the bar B' , thereby permitting the spring b^6 to effect the upward or return movement of the cutting-off tool B^2 . 85

Other modes of applying the principle of my invention may be employed instead of the one explained, change being made as regards the mechanism herein disclosed provided the means covered by any one of the 90 following claims be employed.

I therefore particularly point out and distinctly claim as my invention—

1. In an attachment for automatic lathes, the combination of a stationary support, a 95 reciprocable cutting-off tool mounted in said support, the direction of reciprocation being transverse relatively to the axis of rotation of the lathe head-stock, a reciprocable wedge adapted to engage said tool to effect one reciprocating stroke thereof, a spring for effecting the other stroke thereof, a cam for effecting

ing one reciprocating stroke of the wedge and a spring for effecting the other stroke of said wedge.

2. In an attachment for automatic lathes, 5 the combination of a stationary support, a reciprocable cutting-off tool mounted in said support, the direction of reciprocation being transverse relatively to the axis of rotation of the lathe head-stock, a reciprocating wedge 10 located transversely of and adapted to engage the said tool, a spring connected with the latter adapted to maintain such engagement, a second spring connected with said wedge to effect one reciprocal stroke thereof, a lever 15 adapted to engage said wedge and to effect the other reciprocal stroke thereof, and a cam

engaging said lever and adapted to oscillate same, whereby the reciprocation of said wedge and tool may be effected.

3. In an automatic lathe attachment, the 20 combination of the support B, the spring-actuated bar B' provided with the wedge b', the spring-actuated tool B² provided with the roller b⁵ engaging said bar the lever C provided with the roller c engaging said bar, 25 and with the roller c', and the cam D engaging roller c' as shown and described.

Signed by me this 30th day of July, 1900.
JOHN P. BROPHY.
